UNITED STATES PATENT OFFICE

90,780

DESIGN FOR A BRACELET

Charles B. Oulton, Attleboro, Mass., assignor to
Plastic-Craft Novelty Company, Inc., Attle-
boro, Mass., a corporation of Rhode Island

Application January 30, 1933. Serial No. 47,045

Term of patent 3½ years

To all whom it may concern:

Be it known that I, CHARLES B. OULTON, a citizen of the United States of America, residing at Attleboro, in the county of Bristol and State of Massachusetts, have invented a new, original, and ornamental Design for Bracelets, of which the following is a specification, reference being had to the accompanying drawing, forming part thereof.

Figure 1 is a perspective view of the bracelet, showing my new design;

Figure 2 is a side elevational view of the same with the end rings of the bracelet spread outwardly.

The series of rings forming the bracelet are retained in assembled form by a side link and are shown in Figure 1 in side edge contacting relation. In Figure 2, the outer end rings only are spread outwardly to show relatively movability of the rings forming the bracelet.

I claim:—

The ornamental design for a bracelet, as shown and described.

CHARLES B. OULTON.
